U.S. Cl. D74—1

Fig. 1

Fig. 2

Fig. 3

Fig 4

FIG. 1 is a top perspective view of a support for a stenographic notebook showing my new design;

FIG. 2 is a top plan view thereof;

FIG. 3 is an enlarged showing of the diamond-shaped decoration seen in the center of FIGS. 1 and 2; and

FIG. 4 is another perspective view of the support for a stenographic notebook as it appears in use, the broken line illustration of the notebook being for illustrative purposes only.

The essential features of the design reside in the portions shown in solid lines.

This application is a continuation of my application Ser. No. D.86,626, filed Aug. 18, 1965 which in turn was a continuation-in-part of my application Ser. No. D.82,544, filed Nov. 10, 1964, both of which applications are now abandoned.

I claim:

The ornamental design for a support for a stenographic notebook, as shown and described.
